(57) **CLAIM**

The ornamental design for a temperature trend indicator for use with a surgical and post surgical patient insulation cap, as shown and described.

DESCRIPTION

FIG. 1 is an exploded perspective view of a temperature trend indicator for use with a surgical and post surgical patient insulation cap showing our new design;

FIG. 2 is a left side elevational view, the opposite side being a mirror image thereof;

FIG. 3 is a front elevational view thereof;

FIG. 4 is a rear elevational view thereof;

FIG. 5 is a reverse perspective view showing the underside;

FIG. 6 is a front perspective view showing in use thereof; and, FIG. 7 is a front perspective view of the temperature trend indicator itself shown removed from the surgical and post surgical patient insulation cap.

The dashed lines in FIGS. 1–5 represent the surgical and post surgical patient insulation cap for use with the present invention, and forms no part of the current design. Further, the dashed lines in FIG. 6 represents the surgical and post surgical patient insulation cap for use with the present invention and a user's head, each of which form no part of the current design.
